UNITED STATES PATENT OFFICE.

ALLISON C. BERG, OF CHICAGO, ILLINOIS.

DESIGN FOR AN AUTOMOBILE-BODY.

49,595.

Specification for Design.

Patented Sept. 5, 1916.

Application filed May 18, 1916. Serial No. 98,464. Term of patent 7 years.

To all whom it may concern:

Be it known that I, ALLISON C. BERG, citizen of the United States, residing at Chicago, in the county of Cook and State of Illinois, have invented a certain new, original, and ornamental Design for Automobile-Bodies, of which the following is a full, clear, concise, and exact description.

The design is illustrated in the accompanying drawings in which:

Figure 1 is a side elevation of an automobile; Fig. 2 is a top plan view thereof; Fig. 3 is an enlarged side elevation of the radi-

ator; Fig. 4 is a front elevation thereof; Fig. 5 is a top plan view thereof; Fig. 6 shows the curvature of the body at the section line 6—6 of Fig. 1; and Fig. 7 in like manner shows the curve at the section 7—7 of Fig. 1.

I claim:

The ornamental design for an automobile body as shown.

In witness whereof I hereunto subscribe my name this sixteenth day of May, A. D. 1916.

ALLISON C. BERG.
